METAL DRAWING PRESS

Rudolph W. Glasner, Chicago, Ill., assignor to
 Clearing Machine Corporation, Chicago, Ill., a
 corporation of Illinois

Application August 4, 1934, Serial No. 738,555

4 Claims. (Cl. 113—38)

This invention relates to improvements in metal drawing presses wherein it is desirable to provide means for arresting the movement of the slide during a portion of each cycle of operation and 5 the elimination of costly and cumbersome parts, such as toggles, lazy links, rocker arms, etc., all of which are subject to considerable wear and resultant lost motion, which interferes with the accuracy of the operation of the press.

10 A further object is to provide improved means to stop the slide in its operation, and during such period of rest have the slide stand perfectly still, which heretofore has not been obtained in presses operated by toggle motion.

15 A further object is to provide improved and simple means for varying at will the duration of the period of dwell of the slide, which in presses which are operated by means of cams or toggle motions, cannot be varied except by substituting 20 the operating members with other operating members.

A further object is to provide improved means to operate more than one slide in the press and to provide individual controlling means for varying 25 the length of dwell of each slide or to operate any or all of them continuously or to operate the slides successively, simultaneously, irregularly, or in any combination.

A further object is to provide improved means 30 in a press of this character whereby one or more of the slides may be rendered inactive while the other slide or slides remain active, the said means for this purpose being controllable at will while the parts of the press remain intact.

35 To the attainment of these ends and the accomplishment of other new and useful objects as will appear, the invention consists in the features of novelty in substantially the construction, combination and arrangement of the several parts 40 hereinafter more fully described and claimed and shown in the accompanying drawings illustrating this invention and in which

Figure 1 is a view partly in front elevation, partly in section, partly broken away, and with 45 parts omitted, of a press of this character constructed in accordance with the principles of this invention.

Figure 2 is a vertical sectional view taken on line 2—2, Figure 1.

50 Figure 3 is an enlarged detail sectional view of one of the clutch mechanisms.

Figure 4 is a wiring diagram.

Figure 5 is a view partly in elevation, partly in section and partly broken away, of one of the 55 controls for one of the clutches.

Figure 6 is an enlarged detail sectional view taken on line 6—6, Figure 5.

Referring more particularly to the drawings, the numeral 10 designates generally a press frame provided with a crown 11 and base 12, and a base 5 crown 13.

The crowns 11 and 13 are of a hollow construction to form a lubricant container, for the purposes to be hereinafter set forth.

The numeral 14 designates a slide to which a 10 die 15 is connected, and this slide moves upon vertical guides 16 supported by the press frame.

Connected to the slide 14 are upright members 17 secured by one extremity by means of suitable fastening devices 18 to the slide. Any number 15 of these members may be provided and as their construction and operation is the same, the specific description of one will apply equally as well to them all. The members 17 are of substantial length and pass through bearings 19 which are 20 preferably connected to or supported by the crown member 11. Connected to the members 17 are the ends 20 of eccentric straps 21, which eccentric straps are of integral construction and pass 25 around eccentrics 22 secured to gears 23, and which gears 23 are mounted upon a shaft 24. The shaft 24 passes through the crown 11 and is journaled in suitable bearings 25. The bearings have communication with the interior of the crown so 30 that the lubricating material will find its way into the bearings.

The arms 20 on the eccentric straps 21 are pivotally connected as at 26 with the members 17 and the point of pivotal connection and length of the member 17 is such with respect to the length 35 of the bearing 19 that the pivot 26 will be always maintained within the confines of the outer ends of the bearing so that any stress or strain exerted upon the members 17 will be resisted and the members 17 will be held against lateral movement 40 with respect to the slide 14.

Arranged within the slide 14 is another slide 27 which has connected to it members 28, similar to the members 17, and these members 28, any number of which may be provided, pass through 45 bearings 29, similar to the bearings 19, and which are supported preferably by the crown 11. Mounted upon the shaft 24 and within the container or crown 11, are gears 30 between which are arranged eccentrics, around which are arranged eccentric straps 31. The arms 32 of the straps are pivotally connected to the members 28, similar to the pivotal connection between the arms 20 of the eccentric 21 and the members 17. The bearings 29 are of a length that the pivotal 50 55

connection will be always maintained within the confines of the outer end of the bearings.

The outer slide 14 is reciprocated by means of a shaft 33 arranged within the crown or container and which is journaled in suitable bearings and also passes through a partition 34, which forms a bearing. Secured to the shaft 33 are gears 35 which respectively mesh with the gears 23, and secured also to the shaft 33 is a driving gear 36.

Another shaft 37 is journaled in suitable bearings 38 and also passes through the partition 34, and has secured to it gears 39 which respectively mesh with the gears 30 for rotating them, and connected also to the shaft 37 is a driving gear 40. Thus, it will be seen that when the respective shafts 33 and 37 are rotated, the inner and outer slides 14 and 27 will be correspondingly rotated.

The driving gears 40 and 36 are rotated from any suitable source of power, such as by means of a belt 41 which passes over a pulley 42 connected to one of the shafts 37, and which pulley constitutes a portion of a clutch device.

The gears 40 mesh with each other so as to transmit motion from the drive shaft to the other side of the slide where there is a similar drive connection.

Mounted upon one of the shafts 37—33 are clutch devices and as the construction and operation of all of the clutch devices is the same, the description of one will apply equally as well to the other, with the exception that one of the clutch elements constitutes a pulley or drive connection, whereas the other clutch devices are not driven in the same manner.

The clutch element 43 (see particularly Figure 3) is secured to the shaft 33 for rotation therewith and is preferably connected to the shaft by means of a key connection 44 adapting the element to be moved lengthwise of the axis of the shaft. A spring 45 operates upon the clutch element and tends normally to move it in one direction with respect to the co-operating clutch element 46.

A magnet or electro-responsive device 47 is provided for operating the clutch element 43, and co-operating with the magnet is an armature or solenoid 48 having connection by means of a suitable yoke 49 with the clutch element. When the magnet 47 is energized, the clutch element 43 will be moved against the stress of the spring 45 to effect an operative connection between the clutch element 43 and the shaft 33 so as to cause the clutch element 46 to be rotated with the shaft. When the magnet 47 is de-energized, the spring 45 will move the clutch element 43 into an inactive position with respect to the element 46, and the shaft 33 will then be adapted to rotate independently with respect to the clutch element 46.

Connected with the clutch element 46 for rotation therewith, are gears 49, 50, 51, and over the gear 49 a sprocket chain 52 passes, and this sprocket chain also passes over a sprocket wheel 53, which is connected with the clutch element 54 mounted upon the shaft 37, so that when the gear 40 is rotated, the clutch element 54 which is connected with the gear 40 for rotation therewith, will transmit its motion through the sprocket chain 52 to the clutch element 46 which rotates freely upon the shaft 33. The gears 40 and 36 are mounted loosely upon the shafts 37 and 33, and continuously rotate the clutch elements 54 and 46, but when these elements 54 and 46 are locked with the respective shafts 37 and 33 by the operation of the control device 47, the shafts 37

and 33 will be rotated to reciprocate the respective slides. It will therefore be manifest that by controlling the control devices 47, either one or both of the clutch devices may be rendered active to rotate the respective shafts 37 and 33 or one or both of them may be rendered inactive.

Disposed beneath the bed 12 of the press so as to operate on the other side of the work is another slide 55 which carries a die 56 that co-operates with the dies carried by the slide 27. This slide 55 is reciprocated in a manner similar to the upper slides, and to that end there is provided within the container 13 at the bottom of the press, spaced gears 57 which are secured to a shaft 58 for rotation therewith, and which shaft is mounted in bearings 59. Secured to the shaft 58 are eccentrics 60 encompassed by eccentric straps 61, the arms 62 of which are pivotally connected to members 63 arranged perpendicular to and secured to the slide 55. These members 63 move in bearings 64 preferably supported by the lower crown, and the bearings 64 are of such a length with respect to the point of pivotal connection between the arms 62 and the members 63 and the movement of the pivotal connection that such connection will be always maintained within the confines of the outer end of the bearing 60, so that all lateral stress or strains exerted upon the members 63 will not only maintain them against lateral movement but the slide 55 will be maintained against edgewise and tilting movement.

Meshing with the gears 57 are pinion gears 65 which are secured to a shaft 66 mounted in bearings 67 and also a bearing 68 in a partition 69. All of these parts are located within the lower crown 13. Secured to each of the shafts 66 are gears 70 which mesh with each other so as to operate both sides of the slide in unison. Connected also to the shafts 66 are pinion gears 71 which mesh with the gears 57 for rotating the latter. A clutch device 72, similar in construction to the clutch device illustrated in Figure 3, is mounted upon one of the shafts 66 for rendering the clutch active and inactive.

Secured to the freely rotatable element of the clutch device 72 is a sprocket wheel, over which a sprocket chain 73 passes, and this sprocket chain also passes over the sprocket wheel 50 which is secured to the clutch element 46 that is loosely mounted upon one of the shafts 33, so that motion from the drive pulley 42 will rotate the freely rotatable clutch element on one of the shafts 37, and this in turn will rotate the freely rotatable clutch element on one of the shafts 33, such motion being transmitted through the sprocket chain 73 to the freely rotatable clutch element of the clutch 72 on one of the shafts 66.

A similar control, here shown as an electro-responsive device 47, is provided for rendering the clutch device 72 active and inactive.

It will therefore be manifest that in order to selectively control the operation of the slides 27, 14 and 55, it is only necessary to selectively control the clutch devices on the respective operating shafts for the slides.

Any suitable means may be provided for that purpose, but in the present exemplification of the invention there is provided a circuit control box indicated diagrammatically at 74, to which current is supplied by the feed lines 75—76. This box may be of any desired construction and is provided with circuit control devices 77, 78 and 79, one to control the clutch for the outer slide, designated O in Figure 4, one to control the clutch 75

for the inner slide, designated by the letter I in Figure 4, and one to control the clutch for the lower slide, designated by the letter L in Figure 4.

The numeral 80 in Figure 4, indicates diagrammatically a motor for controlling the operation of the press and which is connected to the feed lines by means of the conductors 81 and 82, a switch or cut out device 83 being provided in one of the connections for the purpose of rendering the motor active or inactive at will.

Secured to a shaft 84, which is mounted preferably in bearings in a bracket 85, are discs or rotatable elements 86, 87 and 88, one for each of the control devices, and as the construction and operation of each of these devices 86, 87 and 88 is the same, the description of one will apply to them all. The element 86 is provided on opposite faces with grooves or channels opening through the faces thereof, having enlarged portions 90. Slides 91 fit within the grooves or channels and are provided with extensions 92 which are preferably threaded. These extensions each pass through a finger 93 preferably provided with a pointed end 94, and a fastening nut or collar 95 is threaded upon the portion 92 so as to clamp the finger 93 as well as the slide 92 in position. The finger 93 is adapted to be moved from the position shown in full lines to the position shown in dotted lines in Figure 5, by loosening the nut or collar 95.

With this arrangement it will be manifest that when the fingers are moved to the position shown in full lines in Figure 5, and secured in that position, they will be in an active position to project beyond the periphery of the element 86, but when it is desired to render the fingers inactive, the fastening nut 95 is loosened and the finger 93 turned to the dotted line position and then secured in this position.

Co-operating with the respective elements 86, 87 and 88 are tappet wheels 97 rotatably supported by shafts 98 journaled in suitable bearings 99. One of these tappet wheels 97 is provided for each of the elements 86, 87 and 88, and also with fingers 93 arranged on opposite faces of the respective elements 86, 87 and 88. When these tappet wheels 97 are rotated by engagement of the tappets or fingers 93 a step by step motion will be imparted to the elements 97, and the rotation of these elements will cause the switches (not shown) to be actuated to establish or interrupt the circuit or current through the switch box to the respective electro-responsive devices 72. This operation will be caused by the fingers on one face of the elements 86, 87 and 88, and the elements 97 will be operated by the fingers on the other face of such elements to re-establish or interrupt the circuit through the electro-responsive devices, so that during the operation of the elements 86, 87 and 88, one set of fingers will open the circuit and one set of fingers will close it.

Obviously, therefore, by arranging the tappets or fingers 93 with respect to each other, the circuits through the various electro-responsive devices may be readily controlled.

It will also be manifest that by setting these fingers 93, the slides 27, 14 and 55 may be controlled in their operation so as to render any one or more of the slides inactive, to cause them to operate upon the work simultaneously, to cause them to operate upon the work successively, or some of the slides may be rendered active while others remain inactive, all according to a predetermined selection by the operator.

Any suitable means may be provided for rotating the elements 86, 87 and 88, but a simple and efficient means embodies a sprocket chain 100 (see Figure 1) which passes over a sprocket wheel 101 on the shaft 84 and also over a sprocket 102 connected to the shaft 103 of a speed reducing mechanism indicated diagrammatically by the reference numeral 104. Another sprocket 105 constitutes a portion of a speed reducing mechanism (not shown but which may be of the ordinary and well known construction), and over this sprocket 105 a sprocket chain 106 passes. This sprocket chain 106 also passes over a sprocket wheel 107 that is secured to one of the shafts 33, so that when the shaft 33 is rotated, motion will be imparted to the sprocket chain 101 to rotate the shaft 84 and with it the elements 86, 87 and 88.

It is thought that the operation of this device will be clearly understood from the foregoing, but briefly stated, it is as follows. The respective slides 14, 27 and 55 are actuated by means of their respective operating mechanisms and the operation of the actuating mechanisms is controlled by the respective clutch devices so that by controlling the clutch devices it will be possible to control or selectively render active or inactive predetermined ones of the slides, thereby placing in the control of the operator a means whereby any one or more of the slides may be rendered inactive, and as before stated, the slides may be caused to operate either simultaneously upon the work, on opposite sides thereof, successively, or some of the slides may be rendered active and inactive, and the relative operation of the slides upon the work with respect to each other may also be controlled or varied. At the same time the period of dwell of the dies upon the work may be controlled or varied, and the length or period of dwell of the dies carried by the respective slides upon the work and with relation to each other may also be varied. This is accomplished by setting the fingers or tappets 93 upon the respective elements 86, 87, 88, according to the desire of the operator and of the work to be performed.

The mechanism, after the fingers or tappets have been set, is automatic in operation and the operation of each of the slides may be automatically commenced and stopped at any time in the cycle of operation of the press or at any point within the 360° of rotation of the driving or actuating shafts of the respective slides.

After the tappets or fingers 93 have been set and the switch 83 closed, the current will flow through the respective electro-responsive devices O, I and L in Figure 4. For controlling the outer slide, the current will flow from the conductor 75, through the conductor 108, electro-responsive device O, conductor 109, switch device 71, conductor 111, back to the conductor 76. Similarly, when the inner slide is to be rendered active, current will flow from the conductor 75, through the conductor 112, electro-responsive device I, conductor 113, through the switch box 78, out of the switch through the conductor 115, back to the conductor 76, and likewise, when the lower slide is to be rendered active, the current will flow from the conductor 75, through the conductor 116, electro-responsive device L, conductor 117, switch box 79, out through the conductor 119, back to the conductor 76.

Thus, it will be manifest that the current may be caused to flow through either one or more of the electro-responsive devices O, I and L, and

by the control or flow of the current through these devices the operation of the respective slides 14, 27 and 55 may be correspondingly controlled. Inasmuch as the operating mechanisms 5 for the upper slides are disposed within the upper crown and the operating mechanism for the lower slide is disposed within the lower crown, and as these crowns constitute lubricant receptacles, the operating mechanisms will be immersed and/or submerged in the lubricant, thereby obviating the necessity of providing separate lubricating ducts or channels leading to the respective parts of the operating mechanisms.

It will therefore be manifest that with the 15 present invention each of the work forming or shaping slides is adapted to be controlled in its operation independently with respect to the operation of the others. It will also be manifest that there is provided controlling means with 20 mechanism adapted to be set so as to cause the operation of the slides to be varied with respect to each other at will. This will render it possible for the operator to cause any two or more of the slides to operate simultaneously or independently 25 with respect to each other, and it is also possible to selectively control the operation of each slide so that the period of dwell or the time of operation with respect to the other slides may be altered or varied so that the operator 30 may have absolute control of the operation of these slides.

It is even possible in the present invention to keep one or more of the slides inactive while the other slides remain active, without the necessity 35 of changing any of the mechanisms of the press or dismantling any of the parts. The structure as disclosed in this application permits adjustments by the operator for the action or inaction of any of the slides, at will, selectively, individually or simultaneously.

While the preferred form of the invention has been herein shown and described, it is to be understood that various changes may be made in the details of construction and in the combination and arrangement of the several parts, 45 within the scope of the claims, without departing from the spirit of this invention.

What is claimed as new is:

1. In a metal drawing press, a plurality of slides 50 operating separately upon the work, actuating means individual to the slides, a source of power, operative connections between the said source of power and each of said actuating means, said connections embodying clutch devices individual to 55 the slides, means individual to the clutch devices for controlling them, the last said means including electro-responsive devices individual to each of the clutches, switch devices individual to the said electro-responsive devices for causing the latter to become energized and de-energized, rotatable elements individual to the switch devices, power means common to said elements for rotating them, and means adjustably connected to each of the said elements and coacting with the 60 respective said switch devices for selectively rendering the clutch devices active and inactive at predetermined times in the cycle of operation of the press to cause the slides to operate in any order or sequence.

2. In a metal drawing press, a plurality of slides 70 operating separately upon the work, actuating

means individual to the slides, a source of power, operative connections between the said source of power and each of said actuating means, said connections embodying clutch devices individual to the slides, means individual to the clutch devices for controlling them, the last said means including electro-responsive devices individual to each of the clutches, switch devices individual to the said electro-responsive devices for causing the latter to become energized and de-energized, 10 rotatable elements individual to the switch devices, fingers adjustably connected to each of the said elements and coacting with the respective said switch devices for selectively rendering the clutch devices active and inactive at predetermined times in the cycle of operation of the press to cause the slides to operate in any order or sequence, and an operative connection between said rotatable elements and said source of power. 15

3. In a metal drawing press, a plurality of slides 20 operating separately upon the work, actuating means individual to the slides, a source of power, operative connections between the said source of power and each of said actuating means and embodying clutch devices, means individual to the clutch devices for controlling them, the last said means including electro-responsive devices individual to each of the clutches, switch devices individual to the said electro-responsive devices for controlling the latter, rotatable elements individual to the switch devices, an operative connection between said source of power and said elements for rotating them, and a finger connected to each of said elements and coacting with the respective said switch devices for selectively operating the switch devices for rendering the clutch devices active and inactive at predetermined times in the cycle of operation of the press to cause the slides to operate in any order or sequence, said fingers being adjustable in one direction with respect to the respective elements to vary in the cycle of operation of the press the time of operation of the fingers on the switches, said fingers being adjustable in another direction with respect to the elements to render said 40 fingers active and inactive with respect to the switch devices. 45

4. In a metal drawing press, a plurality of slides operating separately upon the work, actuating means individual to the slides, a source of power, clutch devices individual to and disposed between the source of power and the respective slide actuating means, electro-responsive devices individual to and disposed in close proximity to the clutch devices for actuating them, switch devices individual to and remote from, but connected to the electro-responsive devices for controlling the latter, said switch devices disposed in close proximity to each other, a rotatable element adjacent each switch device, means operatively connecting said elements for rotation together, means for driving said elements from said source of power, members carried by the respective rotatable elements for engaging and operating the respective switch devices, and means adjustably connecting said members to said rotatable elements, whereby said members may be positioned to be active or inactive with relation to the respective switch devices during the rotation of said elements. 65

RUDOLPH W. GLASNER.
